UNITED STATES PATENT OFFICE.

LEMBERT H. MOULTHROP, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

SPRING-HINGE FOR ELECTRICAL AND OTHER DEVICES.

No. 927,373.

Specification of Letters Patent.

Patented July 6, 1909.

Application filed July 31, 1908. Serial No. 446,344.

To all whom it may concern:

Be it known that I, LEMBERT H. MOULTHROP, a citizen of the United States, residing in the city of Bridgeport, in the county of 5 Fairfield, in the State of Connecticut, have invented a certain new and useful Improved Spring-Hinge for Electrical and other Devices, of which the following is a specification.

10 My improved spring hinge has been more particularly designed for application to and use in the doors or lids of electrical plug receptacles, but as will be readily understood from the description which follows, the invention is applicable to various other devices.

15 In the accompanying drawings Figure 1 is a face view of the underside of the face plate of an electrical plug receptacle or cut out. Fig. 2 is a perspective view of the underside of one of the hinged doors before it is put into the face plate; Fig. 3 is a sectional view on the line 3—3, Fig. 1; Fig. 4 is a view of a modification.

20 The receptacle face plate A illustrated in the drawings is one provided with two doors B, B' hinged at their outer ends and meeting together at the center but with semicircular notches at their meeting edges to form a central opening to receive the rounded head of the plug when it is in the receptacle. As 25 a part of the hinging means I make at least one (and by preference only one) of the hinge pins of a spiral spring. In the specific construction illustrated, one of the hinging pins on one side of each lid is a plain pin P, which is secured in a groove p, in the back of the face plate and projects freely into an opening forming a bearing in the door. The pin P 30 may be secured to the plate A by solder s or by "staking down" the metal of the plate at the edges of the groove p as at s', Fig. 1. The other hinge pin for each lid consists of

35 a spiral spring P¹ secured at one end in the door B (B¹), and at the other end to the face plate A. This spiral spring hinge pin P¹ may be secured to the door and to the plate by solder s or "staking" s', or otherwise, but the securing points should be some distance apart so as to leave a suitable length of 40 spring between the securing points with free play in a groove or hole in the two parts. As will be understood by reference to the drawings, a considerable length of each spring P¹ has free play in its hole h in the door, and a like free play in a part of the open groove p of the face plate. The coils of the springs are so arranged as to tend to keep the doors in their closed positions.

45 If desired the spring hinge may have a straight center pin p² within its coils, as shown in Fig. 4, for strengthening purposes, but the spiral spring soldered or otherwise secured to its opposite ends to the two parts 50 will remain essentially the hinge pin. 65

I claim as my invention—

1. The combination of a fixed plate and a hinged door closing an opening therein and having a hinge pin consisting of a spiral spring secured at its opposite ends to the 60 door and plate respectively.

2. The combination of the face plate of an electrical plug receptacle provided with an opening therein with a door closing the opening in said plate and provided with a hinge 70 consisting on one side of a plain pin and on the other side of a spiral spring, secured at one end to the door and at the other to the plate.

75 In testimony whereof I have signed my name to this specification, in the presence of two subscribing witnesses.

LEMBERT H. MOULTHROP.
